UNITED STATES PATENT OFFICE.

WILLIAM L. MUIR, OF SOUTH MILWAUKEE, WISCONSIN.

WIRE-SPlicer.

1,211,478.

Specification of Letters Patent. Patented Jan. 9, 1917.

Application filed April 3, 1916. Serial No. 88,451.

To all whom it may concern:

Be it known that I, WILLIAM L. MUIR, a citizen of the United States, residing at South Milwaukee, county of Milwaukee, and 5 State of Wisconsin, have invented new and useful Improvements in Wire-Splacers, of which the following is a specification.

My invention relates to improvements in wire splicers.

10 The object of my invention is to provide a simple pocket tool which may be quickly adjusted and conveniently used in connection with a wire splicing tube or member to twist the same after the ends of the strands 15 of wire have been inserted therein.

In the drawings:—Figure 1 is a plan view of my improved wire splicing tool. Fig. 2 is an end elevation showing the end which carries the rigid thumb pieces. Fig. 3 is a 20 view of the opposite end. Fig. 4 is a side view showing the parts in position for inserting the wire. Fig. 5 is a view of a connecting member in which the wire is inserted preparatory to the splicing operation 25 of the tool. Fig. 6 is a fragmentary view showing the wire receiving ends of my improved tool, the intermediate portions being broken away and the twisted or spliced strands of wire being illustrated in position. 30 Like parts are identified by the same reference numerals throughout the several views.

A cylindrical barrel 1, having a longitudinal slot or opening 2 along one side, is provided at one end with a set of projecting thumb-pieces 3. The barrel 1 is partially filled between the thumb pieces 3 leaving, however, a deep groove 5 adapted to receive and hold a set of splicing tubes 6 against 35 rotation, the width of the groove 5 being but slightly in excess of the diameter of the splicing member tubes 6. The opposite end of the barrel 1 is provided with an outwardly extending bead 10 which serves as a 40 swivel-head, and a rotary member 11, provided with projecting thumb-pieces 12, is also provided with a split sleeve or segment 13 which partially encircles the barrel 1 and is prevented from slipping off from the end 45 of the barrel by the swivel-head 10. The margins of the sleeve 13 are sufficiently separated to permit the manipulation of the wire and the splicing tubes 6 into the barrel 1 through the slot 2, when the sleeve segment 50

13 is adjusted with the space between its ends in registry with said slot 2.

The member 11 comprises a cylindrical hub which extends inwardly across the ends of the barrel. It is provided with a deep groove or notch 15 corresponding in form to the notch 5 in the other end or head of the barrel 1. When this groove or notch 15 is alined with the slot 2 and with the groove 5 it is obvious that strands of wire may be inserted in the barrel from one side by 65 merely placing them in the grooves 5 and 15 and allowing them to pass through the slot 2 to the position illustrated in Fig. 6.

In use the strands of wire to be spliced are inserted respectively in the tubes constituting the connecting member 6. These connecting members are not claimed herein as they are in common use for splicing wire, and comprise merely a set of wire-receiving tubes secured together along one side and 70 having a form in cross section resembling a figure 8. One strand 17 of wire is inserted in one of these tubes, and the other strand 18 is inserted in the other tube, whereupon the connecting member 6 is 75 placed in the barrel 1 through the slot 2 with the tubes resting in a superposed position in the groove 5, member 11 being rotated to receive the other end portion of the connecting member 6 in the groove 15. By 80 then rotating member 11, the connecting member 6, with the engaged strands of wire, may be quickly twisted into the form illustrated in Fig. 6, since the open barrel 1 allows the wire and the member 6 to freely 85 rotate while the barrel itself is held from rotation by the hand of the operator engaging thumb-pieces 3. The portion of the member 6 which is engaged in the groove 5 will, of course, be held against rotation. The 90 rotary movement originates from the other end and is applied to the wire through the member 11 from the thumb-pieces or ears 12. If desired, the thumb-pieces or ears 12 may be held stationary and the thumb-pieces 3, together with the barrel, may be 95 rotated with the same effect upon the wire. It will be understood, however, that the thumb-pieces 3 will ordinarily be held in the left hand and the thumb-pieces 12 in the 100 right hand, and that it will be more convenient to rotate the latter.

Owing to the fact that the barrel 1 is tubu-

lar in form and the only projections upon the tool are the thumb-pieces or ears 3 and 12, it is obvious that the tool may easily be carried in the pocket of the user ready for 5 immediate use as required.

I claim:—

1. A wire splicing tool comprising a tubular barrel having a longitudinal slot along one side, and provided with projections at 10 one end, whereby the barrel may be held against rotation, a swiveled member mounted upon the other end of the barrel and provided with operating projections, means connected with the swiveled member for holding strands of wire in parallel relation therein, and means connected with the opposite end of the barrel for holding strands of wire in parallel relation therein, said barrel and swiveled member being adapted to allow 15 strands of wire to extend therethrough longitudinally in such parallel relation.

2. A wire splicing tool comprising a cylindrical barrel provided with a wire-receiving slot along one side thereof, having 20 means for engaging and holding strands of wire or a wire connecting member in fixed relation to the barrel, a swiveled head mounted upon the other end of the barrel, and having a portion projecting longitudi- 25

nally from the barrel and provided with 30 means for holding strands of wire in fixed relation to each other and to the swivel head with the intermediate portions of the strands of wire free to rotate within the barrel.

3. A wire splicing tool comprising a cy- 35 lindrical barrel having a slot along one side through which the wire may be inserted, and also having a head-piece provided with a deep groove through which strands of wire may project from the barrel, the walls of 40 said groove being adapted to hold such strands of wire in fixed relation to each other and to the barrel, all other portions of said barrel having an interior cavity of sufficient size to permit a twisting movement of said 45 strands of wire, and a head-piece mounted to rotate upon the other end of said barrel from that provided with said groove, said head-piece having a similar groove adapted to be adjusted in axial alinement with the 50 barrel and with the groove in said barrel head.

In testimony whereof I affix my signature in the presence of two witnesses.

WILLIAM L. MUIR.
